CLAIM

I claim the ornamental design for a visor for a face mask, as shown and described.

DESCRIPTION

FIG. 1 is a perspective view of a visor for a face mask showing my new design;

FIG. 2 is a right side view thereof;

FIG. 3 is a left side view thereof;

FIG. 4 is a top view thereof;

FIG. 5 is a front view thereof;

FIG. 6 is a bottom view thereof;

FIG. 7 is a rear view thereof;

FIG. 8 is a perspective view thereof, shown attached to a face mask;

FIG. 9 is a right side view of FIG. 8;

FIG. 10 is a front view of FIG. 8; and,

FIG. 11 is an exploded view of FIG. 8, showing the bottom of the visor in perspective.

The broken lines on the visor represent conventional stitching. The mask and person shown in broken lines in FIGS. 8-11 form no part of the claimed design.
